Application December 14, 1935, Serial No. 54,407

9 Claims. (Cl. 201—35)

This invention relates to a new and improved switch and shield construction and more particularly to devices of this character adapted for use in association with variable resistance controls.

In connection with radio receiving sets and also in connection with sound amplifiers for use in radio reception and transmission and in public address systems, it has become customary to use a circuit controlling switch in connection with a variable resistance. The switch and variable resistance may be in the same or different circuits but they are jointly operated by means of a single shaft, the switch being operated at a predetermined point in relation to the control of the variable resistance.

In many such circuits, especially where a low voltage circuit is controlled by the switch as in automobile radios or other such units operated from batteries, a relatively small increase in the resistance in the circuit will have serious effects upon the operation of the apparatus. When used in connection with high voltage circuits the current carried by the switch or variations in that current due to any cause may have an effect upon the adjacently placed variable resistances. These variable resistances are commonly located in portions of the circuits which are highly sensitive so that they are affected by the adjacent switch circuit in a manner to seriously modify the resultant sound reproduction of the circuit.

With associated switch and variable resistance devices which are jointly operated, it is essential that the switch be definitely and accurately located in relation to the resistance and to the actuating mechanism. It is important that the switch have a substantially constant contact resistance throughout an extended operating life, both because of the effect a variable switch resistance will have on the switch circuit and because of undesirable effects a poor switch contact may have upon the adjacent variable resistance. The design of the switch contacts therefore should be such as to minimize arcing with resultant pitting and wear of the contact surfaces and preferably to cause the arcing to occur upon other than the conducting portions of the contact surfaces.

It has been customary to mount the variable resistance upon a flat base member carrying the contact operating member. It has also been customary to support the switch mechanism directly or indirectly from a housing secured to the base member. These housings have tubular side walls usually formed of metal by a drawing operation.

They are usually formed from a flat blank and it is customary to lay out the blank with extending lugs which, after the drawing operation, form securing lugs at the free edge of the tubular side wall for use in securing the housing to the variable resistance base member. It has been found in practice that with common types of sheet metal there is a material variation in the drift of these lugs during the drawing operation so that the lugs are not uniformly spaced in the finished housings. This makes assembly of the housings on the bases difficult where the lugs fit in notches in the base to locate and secure the housing to the base. It will be apparent, particularly where the housing carries a switch, that it is essential that the housing not only be properly positioned relative to the base, but that it be secured thereto in such manner as to prevent looseness and relative rotary movement of the base and housing.

It is an object of the present invention to provide a new and improved switch mechanism.

It is a further object to provide an electrostatic shield for a switch, so associated with a switch that it functions as a portion of the switch mechanism.

It is also an additional object to provide a new and improved switch and shield assembly adapted for assembly with a variable resistance housing.

It is an additional object to provide improved switch contact members.

It is a further object to provide a new and improved unit housing and means for assembling the same upon a base.

It is also an object to provide a method of forming an improved housing with accurately positioned securing means.

It is an additional object to provide devices of the character described which are simple in design and construction and adapted for commercial production.

Other and further objects will appear as the description proceeds.

I have shown a preferred embodiment of my invention in the accompanying drawings, in which—

Figure 1 is a plan view of the switch in the off position, and with the actuating parts on dead center;

Figure 2 is a perspective view of the shield and stop plate;

Figure 3 is a plan view of the switch mechanism with the shield and stop plate in position, the switch and actuating mechanism being in off position;

Figure 4 is a view of the mechanism shown in Figure 3 as seen from below and assembled in the mounting casing;

Figure 5 is a plan view of the actuating member as seen from below, with the movable contact member secured thereto;

Figure 6 is a plan view of the switch mechanism with a fragmentary showing of the kick-off members carried by the shield;

Figure 7 is an unassembled view of the elements making up the switch actuating mechanism;

Figure 8 is a perspective view of the movable contact and a fixed contact;

Figure 9 is a fragmentary section showing the relation between the fixed and movable contacts when in engagement;

Figure 10 is a plan view on an enlarged scale indicating the engagement between the fixed and movable contacts;

Figure 11 is a fragmentary elevation on an enlarged scale showing the method of engagement of the fixed and movable contacts;

Figure 12 is an elevation partly in section showing the switch mechanism and an associated variable resistance mechanism;

Figure 13 is a perspective view of the mounting housing;

Figure 14 is an unassembled perspective view of the housing, switch, variable resistance and grounding plate;

Figure 15 is a plan view of the under side of the combined switch and variable resistance mechanism;

Figure 16 is a plan view of a sheet metal blank for the housing member; and

Figure 17 is a fragmentary perspective showing the method of locating and connecting the housing and base member.

As best shown in Figure 1, the switch mechanism is mounted on a base plate 20 which may be formed of any suitable non-conducting material, such, for example, as sheet Bakelite or other artificial resin. The base 20 is circular in plan and in the form shown is provided with locating and securing notches 21, the purpose of which will be discussed hereafter. The fixed contact members 22 and 23 are secured to the base plate 20 by means of the hollow rivets 24 and 25. These contact members 22 and 23 are provided with the connecting lug portions 26 and 27 which extend through slots in the base 20 as clearly shown in Figure 4. The body portion of the fixed contact members is held in flat engagement with the face of the base 20 and the fit of the securing lug portions 26 and 27 in the openings in the base 20 prevents rotation of the members about their securing rivets 24 and 25. The contacts are thus firmly and positively retained in place. These fixed contact members 22 and 23 are provided with offset portions 28 and 29 respectively, which are provided with angular faces 30 and 31 for engagement by moving contacts. These portions 28 and 29 are raised clear from the base plate 20 an amount sufficient to permit a portion of the movable contact to pass between the base and the fixed contact portion, as will be described hereafter.

The movable switch arm 32 may also be formed of sheet Bakelite or similar artificial resin or other non-conducting material. The under side of this member is shown in Figure 5 and the member is provided with the opening 33 which fits upon the pivot pin 34. The movable contact 35 comprises a pair of approximately U-shaped metallic members 36 and 37 as best shown in

Figure 8, which members are secured to the member 32 by means of the tubular rivets 38 and 39. The member 37 is provided with the downturned fixed contact engaging portions 40 and 41, while the member 36 is provided with the corresponding upturned fixed contact engaging portions 42 and 43. The thin cover member 44 is similar in shape to the member 32 and overlies that member so as to cover the heads of the movable contact securing rivets 38 and 39 and to thus insulate the movable contact from the switch operating mechanism. This member 44 may be formed of sheet Bakelite or similar material.

The operating cam 45 is U-shaped in vertical section, as clearly shown in Figure 7, having upper and lower horizontal legs 48 and 49, joined by a vertical wall 50. The legs 48 and 49 are provided with perforations 51 and 52 to fit on the shank 53 of the pivot pin 34. The upper leg 48 is provided with the notch 54 adapted to receive an actuating pin 55 carried by the disc 56 rotatable with the variable resistance arm, as shown in Figure 12. The lower leg 49 has a T-headed lug 57 extending therefrom, this lug extending through the slot 58 in the head 59 of the pivot pin 60.

The pitman 60 carries the compression spring 61, one end of which engages the shoulder 62 on the pitman while the other end engages the abutment member 63. This abutment member 63 is provided with an opening 64 through which the end 65 of the pitman 60 slides. The body of the abutment member 63 extends through corresponding openings in the switch arm cover member 44 and the movable switch arm 32. The tail 67 of the member 63 fits into aligned notches 68 and 47 formed in the ends of the arm 32 and member 44. This abutment member thus serves jointly with the pivot 34 to hold members 32 and 44 together.

The pivot pin 34 is provided with the enlarged portion 69 below which is the shoulder 70. The perforation 33 in the member 32 and the corresponding perforation in the member 44 fit over the enlarged portion 69, as clearly shown in Figure 12. The enlarged portion 71 on the pivot pin below the shoulder 70 serves to space the switch mechanism from the base plate 20. As shown in Figure 12, the lower end of the pin 34 is riveted over at 72 to retain the pin in place in the base plate 20. The upper end of the pin 34 is also riveted over at 73 to retain the cam member 45 in place on the pin. The cam member then serves to retain the switch arm and cover member in proper position on the enlarged portion 69.

The shield 74 is provided with three downturned legs 75, 120 and 121 which are provided with the reduced securing lugs 76, 122 and 123. These securing lugs 76, 122 and 123 are of a size 80 to fit in the notches 21 formed in the switch base plate 20 and are so positioned as to register in these notches as shown in Figures 3 and 4. The shield member 74 is also provided with the two downturned stop lugs 77 and 78 adjacent the recess 124 formed in the shield. As shown in Figure 3, these lugs are engaged alternately by the operating cam 45 at its two limits of movement. The lateral extended portions of the switch arm members 32, 44 also alternately engage the inner 70 faces of the legs 120 and 121 at their limits of movement as shown in Figure 3. The shield 74 is provided with the upstanding lug 79 which serves as a limiting stop for the rotary contact arm of the associated variable resistance. The 75

center portion of the shield member 74 is formed with the downturned lugs 80 and 81 which in the operation of the switch, as will be hereafter explained, serve to assist in breaking contact between the fixed and movable contact members.

The switch is assembled upon the base 82 of the variable resistance by means of a supporting housing 83 which is preferably formed from sheet metal. This housing 83 is tubular in shape, having an inturned peripheral flange 84 at one end. The flange 84 is provided with inwardly extending portions 85, each of which is provided with a slot 86 adapted to receive one of the securing ears 76, 122 or 123 formed on the shield 74. The portions 75, 120 and 121 of the shield engage the inner surface of the base 20 adjacent the notches 21 through which the ears 76, 122 and 123 pass, and by passing these ears through the perforations 86 and bending them over, the shield 20 and switch base carrying the switch mechanism are mounted in the housing 83. This is clearly shown in the lower portion of Figure 12.

As shown in Figure 14 the base 82 of the variable resistance is provided with a pair of notches 87 and 88, which are diametrically opposite each other and equally spaced from the extended portion 89 of the base member, which portion carries the connecting lugs 90, 91 and 92. These lugs 90, 91 and 92 serve to connect the movable contact and the ends of the variable resistance in the desired circuit. In addition, the base 82 is provided with further notches 93, 94, 95, 96 and 97. The notches 87, 88, 93, 94, 95, 96 and 97 are all positioned to receive corresponding lugs 104, 105, 103, 102, 101, 98 and 99 on the lower edge of the housing 83. The wall of the housing 83 is cut away between the lugs 98 and 99, as shown at 100 in Figures 13 and 14, in order to receive the extended portion 89 of the base member 82. The notches 93 to 97 inclusive, and the coacting lugs 98, 99, 101, 102 and 103 are so proportioned and located that the lugs will fit into the notches with a slight clearance therein as shown somewhat exaggerated at 127 on Figure 17. The remaining lugs 104 and 105 are located at opposite ends of a diameter of the housing and fit into the notches 87 and 88 which are similarly located on the base member 82. These notches and lugs are made of such size that the lugs fit closely in the notches and they serve as a primary locating means to accurately and exactly position the housing upon the base member.

The variable resistance comprises a flat, carbonaceous type of resistor 106, which is secured on the base member 82 by the lugs 90 and 92 in any customary manner. The arm 107 carrying the contact shoe 108 is rotated by means of the shaft 109. The disc 56 is also secured to the shaft 109 by means of a reduced portion 111 of the shaft which is riveted over against a washer 112. This disc carries the pin 55 which serves to engage the notch or fork 54 in the actuating cam 45 as above described. The disc 56 is provided with an arcuate radially extended portion 113, the edges of which are adapted to engage the upturned lug 79 on the shield member 74 to limit rotation of the disc and the associated parts.

The assembly may be provided with a grounding member 114 which is best shown in Figures 14 and 15. This member 114 is secured to the variable resistance base 82 by means of the bushing 115 which supports the shaft 109. The member 114 is formed of electrically conductive metal

and is provided with upturned extensions 116 which may serve to fasten the assembly to a mounting base or chassis or which may merely extend through openings in the mounting member to prevent rotation of the assembly about its axis. In the latter case, the assembly is mounted by nut 125 on the bushing 115. The member 114 is also provided with offset extensions 117 which are offset to bear against the outer face of the variable resistance base 82. As best shown in Figure 15, these extensions 117 are engaged by the lugs 98 and 99 formed on the housing member 83. Consequently the member 114 serves to ground the housing to the bushing 115, which is usually grounded by connection to a metal chassis or supporting panel.

It will be noted that the body portion of the grounding plate which is located on the opposite side of the resistance base 82 from the resistance strip 106 and aligned with that strip, is spaced from the base 82 as clearly shown in Figures 12 and 14. This results in materially reducing the capacity coupling between the resistance strip and the grounded plate.

It is believed that the method of assembling the switch elements on the base plate 20 will be readily understood from the drawings and the description. The base may be blanked out of sheet material, with the various notches and perforations formed at a single operation so that it is comparatively inexpensive to make and much cheaper than molded insulation switch supporting housings which are in general use. The two fixed contacts 22 and 23 are inserted and secured in place by their tubular rivets 24 and 25. The pivot member 34 may then be secured in place in the base 20 by riveting over the lower end of the member 34, as shown at 72 in Figure 12.

As a separate operation the movable contact assembly 35 is secured to the movable switch arm 32 by means of the rivets 38 and 39. The switch arm 32 may be formed of sheet insulating material in the same manner as the base 20, being blanked out and perforated in a single operation. After the movable contact assembly 35, comprising members 36 and 37, is secured to the movable arm 32, the abutment member 63 may have its body portion inserted through the slot in the arm and the contact arm cover member 44 is then placed over the contact arm 32, a corresponding perforation fitting over the body 63 of the abutment member. The tail 67 of the abutment member is then forced downwardly to grip the member 44 and fix the members 32 and 44 in assembled relation.

The switch arm, movable contact and abutment assembly may next be placed on the pivot pin 34 resting against the shoulder 70, as best shown in Figure 12. The operating cam 45 may next be placed on pivot pin 53 resting on shoulder 69 and the head of the pin riveted there as shown at 73 in Figure 12. The pitman 60 is next secured to the cam 45 by hooking the slot 58 over the T-head 57 of the cam and the spring 61 assembled on the pitman. There are no stops limiting the rotation of the cam 45 on pivot 34 so that the cam and pitman assembly may be swung to one side and the end of the pitman properly inserted in the slot 64 in the abutment member 63.

The next step in the assembly is the location of the shield 74 in relation to the base 20 by placing the lugs 76, 122 and 123 in the corresponding notches 21 so that the cut-away portion 124 is located above the cam 45, as best shown in Fig-

- ure 3. During this assembly the switch parts are held so that the switch arm members 32 and 44 fit between the legs 120 and 121 of the shield, and the cam 45 fits between the stops 77 and 78. 5 Similarly, with the parts positioned in this manner, the pitman 60 and coil spring 61 fit between the kick-off members 80 and 81.

The shell or housing 83 is next assembled on the switch assembly, with the lugs 76, 122 and 123 10 passing through the openings 86 formed in the extended portions 85 of the flange 84 of the housing. The ears or lugs 76, 122 and 123 are then bent down firmly against the extended portions 85 and serve to maintain the shield and switch base carrying the switch assembly in proper assembled relation in the housing 83.

The variable resistance assembly shown in Figures 12 and 14 in its specific form is not part of the present invention and its method of assembly need not be described in detail. 20

When the thimble or bushing 115 is assembled to the base 82, the shield member 114 is also assembled and is held in place by the bushing 115. It must be so assembled in relation to the base 25 that the connecting portions 117 are located adjacent the notches 96 and 97 in the base. The variable resistance actuating arm and collecting rings are assembled in the usual manner and the assembly held in place by means of the C-washer 130 fitting in a groove 131 in the shaft 109. When the switch assembly carried in the housing is assembled on the variable resistance assembly, it is necessary that the switch mechanism be in proper relationship with the actuating pin 55 so that 30 35 that pin will properly enter the notch 54 in the cam 45 when the variable resistance is rotated. For example, the parts may be assembled with the switch in the "on" position and the variable resistance contact member turned well to the 40 limit of clockwise movement. This will insure proper cooperation of the parts after assembly. There is no difficulty in getting the housing and variable resistance base plate in proper registration for assembly since the cutout portion 100 in 45 the housing fits over the extended portion 89 of the base 82.

It will be understood that the lugs 98, 99, 101, 102 and 103, fit somewhat loosely in their corresponding notches in the base plate so that the 50 accurate assembly of the parts is caused by lugs 104 and 105 which fit very closely in the associated notches in the base plate. When the housing and switch assembly is assembled on the base plate, the lugs 98, 99, 101, 102, 103, 104 and 105 55 are all bent over and pressed down firmly to properly maintain the parts in fixed relation. The lugs 101 to 105 inclusive bear against the under face of the base 82, while the lugs 98 and 99 bear against the portions 117 of the grounding member 60 114.

It will be apparent that the shield 74 is effectively grounded to the housing 83 by means of the lugs 76, 122 and 123 which are pressed firmly into engagement with the portions 85 of the housing. 65 The housing is then positively grounded to the plate 114 by contact of lugs 98 and 99 with portions 117. Thus the shield, housing and ground plate are all positively grounded to the thimble or bushing 115. All of the current carrying portions of the switch assembly are thoroughly 70 covered by the shield member 74 which is interposed between them and the variable resistance strip 106. The actuating portions of the switch, including the pivot pin 34, cam 45, pitman 60, 75 spring 61 and abutment member 63 are all insu-

lated from the current carrying portions of the switch by means of the insulated switch arm 32 and insulated switch arm cover 44.

The shield 74 will be seen to perform a number of functions. It serves as a securing means for 5 securing the switch assembly to the housing. It serves to provide a stop to limit rotation of the variable resistance contact arm by means of the stop member 79 which is engaged by the extension 113 on the disc 56. It serves as a stop to 10 limit movement of the switch arm in each direction by means of the legs 120 and 121. It further serves to limit the movement of the cam 45 by means of stops 77 and 78. It is to be noted at 15 this point that, by contact with these stops at either end of the limit of movement, the metal actuating portions of the switch assembly are also grounded.

An additional function of the shield plate is provided by the kick-off lugs 80 and 81. The 20 function of these lugs is shown in Figure 6. The operating cam 45 is swung from the dotted line position of Figure 6 in clockwise direction to cause the switch arm and the movable contact assembly 35 to move to the left out of engagement with 25 the fixed contacts 22 and 23. As the parts move past the dead center in the clockwise direction, as seen in Figure 6, the force stored in spring 61 thrusts against the abutment 63 and tends to move the switch arm assembly to the left. Resisting this movement is the gripping action of the movable switch members 36 and 37 upon the 30 fixed contact member. This resistance may be considerable if the contacts have become somewhat roughened or pitted in use by arcing. 35

The continued movement of the cam and pitman to the right or in the clockwise direction, with the movable contact still in engagement with the fixed contacts, will bring the side of the spring 61 against the stop 80. This stop 80 will then 40 act as a fulcrum and, in addition to the force of spring 61, the thrust to the right against the lower end of the pitman in Figure 6 by the cam 45 will cause a movement of the upper end of the pitman to the left, which will positively break any 45 connection between the movable and fixed contact members. When moving the switch arm in the opposite direction the kick-off lug 81 will have a similar effect in positively initiating the movement of the switch arm in the clockwise direction. It will be understood that the parts are so proportioned and located that these kick-off lugs will merely initiate the movement which will be completed by the force stored in the spring 61 independently of the speed of movement of the 55 actuating cam 45.

The movable and fixed contacts shown in detail in Figures 8 to 11, are specially designed to insure a firm, clean contact and to prevent arcing from occurring between the contacting surfaces. 60 The upper member 36 is formed of heavier material and is substantially rigid. The lower member 37 is formed of lighter spring material and is relatively flexible. The contact arm assembly is biased downwardly toward the supporting plate 20 by means of the thrust of the spring 61 against the abutment member 63. The pivot portion of the arm is held spaced from the base 20 by means of the enlarged portion 71 of the pivot pin. The openings in the arm members fitting about the 70 portion 69 of the pin have a somewhat loose fit so that the spring 61 may thrust the outer or free end of the arm downwardly without binding the arm on the pivot, so that the downturned portions 48 and 41 of the lower member 37 engage the

inner face of the base plate 20. The contact portions 28 and 29 of the two fixed contacts are spaced upwardly from the inner face of the base 20 so that the downturned contact edges 40 and 5 41 slide under the fixed contact portions 28 and 29. This is clearly shown in Figure 9.

The contact portions 36 and 37 spring apart sufficiently to grip the fixed contact portions 28 and 29 firmly between them. The major portion 10 of the spring action is afforded by the lighter, more resilient lower contact member 37. The contact edges 30 and 31 of the fixed contact portions 28 and 29 are formed upon an angle to the contacting edges 40 and 42 and 41 and 43 of the 15 movable contact member. Thus it will be seen from an examination of Figure 10 that the normal point of contact between the fixed and movable contacts will be adjacent the free end of the movable contacts and adjacent the inner end of 20 the fixed contact edge.

Also as shown in Figure 11, due to the downward bias given the movable contact members, the initial contact between the movable and fixed contacts will be between the heavier movable contact member 36 and the fixed contact 29. This 25 will cause any initial arcing to take place between the heavier movable contact and the comparatively heavy fixed contact. If, through repeated operation, the point of initial contact between the movable contact and the fixed contact is worn away, the point of initial contact will 30 progress down the sloping fixed contact edges 30 and 31 toward their outer ends.

The arcing on opening or closing the switch 35 occurs on surfaces which are not normally in contact when the switch is closed. This will be apparent from Figures 9 and 11, which show that the initial and final contacts which may arc are on the upturned lip 43 of the movable contact. 40 When the switch is in closed position this upturned lip is not in engagement with the fixed contact member 29. Consequently, any arcing or pitting or fouling due to arcing which may occur will not affect the surfaces in contact when the 45 switch is closed and carrying the current. It will also be apparent that the spring action of the two movable contact members and their separation by the fixed contact members, causes a wiping action over the final contact surfaces which will keep 50 these surfaces clean and free from oxide or foreign matter. The switch consequently will have a low resistance even after extended use.

By blanking my housing member from the strip sheet metal as shown in Figure 16, I am enabled 55 to use usual types of commercial sheet steel and have the housings uniformly and accurately positioned relative to the fixed base of the resistance unit. As has been stated above, the diametrically opposite lugs 104 and 105 are the ones which are 60 used to positively locate the housing relative to the base, the remaining lugs somewhat loosely fitting in their associated notches. The blank is stamped from the strip sheet metal in such a manner that the opposite lugs 104 and 105 are 65 aligned along the line of grain or fibre of the metal.

It will be understood that sheet metal of commercial types has a grain or fibre running lengthwise of the sheet metal, this grain or fibre being 70 produced by the normal rolling operations used in forming the sheet metal. It has been found that, due to this grain and also to some extent due to variations in the internal structure of the sheet metal when produced commercially, there is considerable drift in the lugs blanked out during the 75

forming operation. It will be understood that a blank substantially as shown in Figure 16 is cut or stamped from sheet metal and then by the forming or drawing operation reduced to the shape shown in the upper portion of Figure 14. 5 This forming or drawing operation brings the flat blank to a substantially tubular form and it has been found that the various lugs will drift somewhat so that they are not spaced after the drawing exactly in the same relation as before the 10 drawing. I have found that by using only two lugs for the actual location I can assure that these lugs will be drawn substantially without relative drift between them if they are blanked out from the sheet metal on opposite ends of a 15 diameter of the blank aligned along the line of grain or fibre of the metal. This enables the forming of a cover which will be accurately positioned on the base and which may be cut from commercial types of sheet metal. This results in 20 a very considerable saving in expense in the forming of these blanks. While metal may be secured without substantial grain, it is more expensive than usual types of metal and also difficult to secure it with absolute uniformity of structure. 25

The grounding plate 114 is an important feature of the entire combination shown. This plate has a double function in serving as a grounding connection and also by means of the ears 116 serving as a locating device for locating and preventing rotation of the unit after it is assembled 30 on a chassis. It will be understood that positive means preventing rotation of the unit is important in addition to the clamping action of the securing nut 125. This is for the reason that it may 35 take considerable torque to operate the switch, and also since the rotation of the shaft is stopped by a positive abutment in the housing there is a tendency to gradually rotate the assembly unless it is positively locked against rotation relative to 40 its support.

Another important feature of the grounding plate 114 is that the portions which overlie the resistance strip 106 are relatively small and are also bent away from the base 82 so as to minimize 45 any capacity effect between the resistance strip and grounding plate. This has a desirable effect when these units are used in highly sensitive circuits for which they are adapted.

It will be noted that the various ears on the 50 lower edge of the housing member 83 are all shown with a relatively wider portion adjacent the body of the housing, which wider portion fits in the notches in the base member 82. This wider portion is of substantially the same extent as the 55 thickness of the base 82. This makes it simple and easy to bend over the reduced portions of the lugs against the outer face of the base plate without any distortion of the body portion of the lug or tendency to spring it outwardly as the end 60 is bent over.

While I have shown certain preferred embodiments of my invention, these are to be understood as illustrative only, as it is capable of change and variation to meet differing conditions and requirements and I contemplate such changes and modifications as come within the spirit and scope of the appended claims. 65

I claim:

1. In a switch assembly, a non-conducting 70 base, a snap switch supported by the base, a metallic shield adjacent to the switch, integral legs on the shield engaging the base and maintaining the shield spaced therefrom, and members extending from the shield into the path of 75

- movement of switch parts to be engaged by said parts to assist in switch movement.
2. In a switch assembly, a non-conducting base, a snap switch supported by the base, a metallic shield adjacent to the switch, integral legs on the shield engaging the base and maintaining the shield spaced therefrom, and a plurality of members extending from the shield into the path of movement of switch parts to be engaged by said parts during switch operation, certain of said members assisting in switch movement and other of said parts serving as limiting stops for switch movement.
3. In a switch assembly, a non-conducting base, a snap switch supported by the base, a metallic shield adjacent to the switch, and a plurality of members extending from the shield into the path of movement of switch parts to be engaged by said parts during switch operation, certain of said members assisting in switch movement and other of said parts serving as limiting stops for switch movement.
4. In combination, a tubular metallic housing, non-conducting end members for said housing, a switch secured to one end member, the other end member providing a thin plate-like base, a variable resistance carried against the inner face of said base, common actuating means for the switch and variable resistance, a metallic shield between the switch and variable resistance, said shield being secured to the metallic housing, a conductive grounding plate secured to the outer face of the thin base carrying the variable resistance, and an electrical connection between the housing and said grounding plate, the portion of the grounding plate overlying the resistance being spaced from the thin base to reduce capacity coupling between the resistance and the grounding plate.
5. In a variable resistance device, a thin flat non-conducting base, an arcuate resistance strip carried against the inner face of the base, rotatable contact means carried by the base, a metallic housing enclosing the resistance, a conductive grounding plate carried against the outer face of the base, and an electrical connection between the housing and grounding plate, a portion of the grounding plate overlying the resistance, said portion being spaced outwardly from the base to reduce capacity coupling between the resistance strip and the grounding plate.
6. In a switch assembly, the combination of, a substantially flat non-conducting base, a snap switch mounted on said base, a metal casing for the switch, said casing having a substantially cylindrical metal side wall encircling the base, a part turned in from the edge of the side wall and overlying the outer face of the base to support the same against outward displacement with respect to the side wall, a plurality of metal tongues having reduced end portions forming shoulders and tangs, said base having apertures through which the tangs pass so that the shoulders on said tongues bear against the inner face of the base, the outer ends of the tangs being bent over the part turned in from the edge of the casing side wall so that the base is confined between said part and the shoulders on the tongues, and a metal plate carried by the tongues and overlying the switch parts inside said casing.
7. In a switch assembly, a metallic casing having an open end and an inwardly directed abutment integral with the side wall of the casing at said open end, said abutment having an aperture therethrough, an insulating base in the casing supported by said abutment against outward displacement with respect thereto, said base having an aperture in alignment with the aperture of the abutment, switch parts mounted on said base, a tongue having a reduced end portion providing a tang and a shoulder, the tang projecting through the aligned apertures of the base and abutment and being clinched over the abutment to confine the base between the abutment and said shoulder and electrically connect the tongue with the casing, and a metal shield integral with the tongue and overlying the switch parts inside said casing.
8. In a combined rheostat and snap switch for use in radio circuits, a single substantially cylindrical metal shell, one end of which contains the rheostat, and the other end of which contains the snap switch, a non-conducting base having the snap switch mounted thereon and closing one end of the shell, and a shield between the snap switch and the rheostat comprising, a transverse metal wall having an integral side wall portion connected to said base and contacting part of the shell so that the shield and shell are electrically connected and the transverse wall is held in position dividing the shell into a switch compartment and a rheostat compartment, and said transverse wall having an opening through which the actuating mechanism of the snap switch is rendered accessible for actuation by a part moving with the movable element of the rheostat.
9. In an electrical control of the character described, a substantially cylindrical metal shell, a substantially flat non-conducting base, a snap switch mounted on the inner face of the base, a transverse metal wall overlying the switch and having an integral side wall portion spanning the distance between it and the base, interengaging means on the side wall portion and the base for holding said transverse wall against rotation with respect to the base, said transverse wall being of such size as to fit inside the metal shell with its side wall portion closely adjacent thereto, means on the metal shell engaging over the base to confine the connected base and transverse wall between it and a portion of the metal shell with the base closing one end of the shell and the transverse wall electrically connected to the shell, said transverse wall having an opening therethrough, a metal actuating cam connected with the snap switch and having a part projecting through said opening, stop means integral with the transverse wall engageable by the metal actuating cam for limiting motion thereof and for grounding the metal actuating cam to the transverse wall and shell, said cam substantially covering the opening to coact with the transverse wall in shielding the switch from the space in the shell beyond the transverse wall, a manually operable control instrumentality in said space, and a driving connection between said instrumentality and the cam part projecting through the opening.
